(57) **CLAIM**

The ornamental design for a 2-D cube carabiner, as shown and described.

DESCRIPTION

FIG. 1 is a plan view of the top and bottom sides, which are mirror images, of my new design for a 2-D cube carabiner. FIG. 2 is a front plan view of the carabiner shown in FIG. 1.

FIG. 3 is a rear side plan view of the carabiner shown in FIG. 1.

FIG. 4 is a right side plan view of the carabiner shown in FIG. 1.

FIG. 5 is a left side plan view of the carabiner shown in FIG. 1; and,

FIG. 6 is a top perspective view of the carabiner shown in FIG. 1.
